UNITED STATES PATENT OFFICE.

AUGUSTUS HERBERT BRAID, OF SUMMERTON, SOUTH CAROLINA.

WIRE-TENSION DEVICE.

Application filed July 5, 1924. Serial No. 724,378.

To all whom it may concern:

Be it known that I, AUGUSTUS H. BRAID, a citizen of the United States, and a resident of Summerton, in the county of Dorchester and State of South Carolina, have invented certain new and useful Improvements in Wire-Tension Devices, of which the following is a specification.

My invention is an improvement in devices for causing a tension on a wire as the latter is drawn in the direction of its length, and it consists in the combinations, constructions and arrangements herein described and claimed.

An object of the invention is to provide a simple, reliable and inexpensive device which is adapted to impose a tension which may be varied within a considerable range on a wire at the time the latter is moved in the direction of its length.

A further object of the invention is to provide a device of the character described which can be constructed to impose tensions on any number of wires up to a given number and which then can be adapted by the addition of but relatively few additional parts and at but relatively little cost to impose tension on additional wires.

Other objects and advantages will be apparent from the following description, considered in conjunction with the accompanying drawings, in which:

Figure 1 is a longitudinal vertical section through a wire tension device embodying the invention, the view being taken substantially along the line 1—1 of Figure 2, and

Figure 2 is a fragmentary plan view of the device with portions thereof broken away.

A device embodying the invention is designed particularly for use in straightening and placing a tension on magnet wire during the handling of such wire in the manufacture of electrical equipment but is adapted for use in placing a tension on any flexible elongated member of small size as will be understood from the following description.

In carrying out the invention, I may make use of an upright support 1 which may be a plate disposed vertically edge-wise, a standard or the like. A horizontal table 2 is formed with an integral attaching portion 3 depending therefrom at one edge thereof, the attaching portion being secured

by fastening devices, such as the bolts and nuts indicated at 4 to the upper end portion of the support 1. The upper face of the table 2, which preferably is formed of steel, is smooth and plane and is disposed above the level of the upper end of the support 1.

A frame includes a pair of elongated side members 5, only one of which is shown in the drawings. However, it will be understood that the side members 5 are disposed at opposite ends of the table 2 in right angular relation to the latter and that each side member 5 is secured to the table 2 in any suitable known manner, as by means of the cap bolts 6, the opposite ends of the side member extending laterally of opposite sides of the table. The side member 5 is shown as being secured at its opposite ends by screws 7 to corresponding ends of a pair of parallel end members 8. The end members 8 preferably are formed of wood and are disposed in spaced parallel relation to the table 2. It of course will be understood that the end members 8 will be connected at the ends thereof which are remote from the side member 5, which is shown in the drawings by the second side member which is not shown in the drawings.

Each end member 8 is provided with a plurality of spaced apart horizontal guide openings 9 which extend transversely through the end member. Corresponding guide openings 9 of the two end members are axially aligned and are located slightly above the level of the upper surface of the table 2. A wire 10 can be led through a guide opening in one end member 8, then across the upper face of the table 2 and finally through the corresponding guide opening 9 of the other end member. The

means for causing a tension on the wire during its longitudinal movement between the corresponding guide openings of the two end members 8 includes a presser block 11 having a post 12 upstanding therefrom and extending loosely through a vertical opening 13 in a horizontal guide 14 for said post. The guide 14 is the horizontal leg of a member which is angular in cross sectional contour and which is supported on the table 2 in spaced parallel relation to the latter by suitable fastening devices, such as the bolts 15. The vertical leg of said angular member is indicated at 16. Brackets 17 secured by screws 18 to the vertical leg 16 support a horizontal shaft 19. A lever

105
110
115

20 for actuating the presser block 11 by means of pressure imposed upon the upper end of the post 12 is fulcrumed adjacent to one end thereof on the shaft 19 and extends 5 through a vertical slot 21 in the upper edge of the vertical leg 16 across the upper end of the post 12. A second lever 22 is fulcrumed at one end on horizontal pivot element 23 which is carried by the side member 5. The lever 22 is disposed at a lower level than the lever 20. A horizontal shaft 24 extends transversely through the lever 22 intermediate the length of the latter. The lever 20 is connected to the shaft 24 by a 10 tension spring 25. The lever has a laterally turned handle portion 26 at its free end and it will be manifest that manipulation of the handle 26 to cause the lever 22 to swing downwardly about its fulcrum will cause a 15 pull to be imparted through the spring 25 to the lever 20, tending to swing the latter downwardly about the axis of the shaft 19, whereby the presser block 11 will be moved downwardly toward the table 2. The wire 20 which extends across the table 2 between the latter and the presser block 11 is partially received in a transverse groove 27 in the lower face of the presser block. The groove 27 preferably is V-shaped in cross 25 sectional contour. It will be manifest that the wire passing between the table 2 and the presser block will be under tension when the lever 22 is swung downwardly in the manner described and that the tension on 30 the wire will vary according to the extent of downward swinging movement of the free end of the lever 22. A desired tension on the wire can be maintained when obtained by preventing further swinging movement of the lever 22 about its fulcrum from 35 a desired position. To this end, my invention provides a holding bar 28 having a slot 29 in one end through which an end portion of the shaft 24 extends loosely and being bifurcated at its other end by a slot 40 30 through the shank of a horizontal cap screw 31 which is in threaded engagement with an opening in the side member 5 extends. The cap screw can be tightened 45 against the bifurcations of the holding bar 28, thus clamping the latter to the side member 5, whereby the lever 22 will be held 50 against swinging upward movement about the axis of the pivot element 23 from a desired position and a desired tension on the wire which extends between the presser block and the table 2 will be maintained. The straightening and the handling of the wire in the manufacture of electrical equipment or in like use thus will be facilitated.

60 It will be understood from the foregoing that a presser block and post, a lever 20 and a tension spring 25 may be provided for each pair of aligned guide openings in the 65 respective end members 8 and that a plu-

rality of wires can be straightened and maintained under tension at the same time through the use of the device, the number of such wires being limited only by the number of pairs of aligned guide openings 9 70 when a presser block and presser post, lever 20 and tension spring 25 associated with the remaining parts of the device in the manner hereinbefore described having been provided for each pair of guide openings 9. 75

Obviously, the invention is susceptible of embodiment in forms other than that which is illustrated in the accompanying drawings, and I therefore consider as my own all such modifications and adaptations thereof as 80 fairly fall within the scope of the appended claims.

I claim:—

1. A wire-tension device comprising a table, a pair of wire guides respectively disposed at opposite sides of the table for guiding an axially movable wire across said table, a presser block completely disposed above and free from said table and having limited vertical movement in respect to the table, said presser block having a groove in its lower face for engaging with the portion of the wire which extends across said table, said presser block having a post upstanding therefrom, means engaging with said post for guiding the latter during the movements of said block with respect to the table and for limiting the upward movement of said block, and tension means engaging said post for urging the latter axially toward 100 said table.

2. A wire-tension device comprising a table, a pair of wire guides respectively disposed at opposite sides of the table for guiding an axially movable wire across said table, a presser block disposed above said table and having limited vertical movement in respect to the table, said presser block having a groove in its lower face for engaging with the portion of the wire which extends across said table, a lever swingable vertically for imposing a downward pressure on said block, a second lever swingable vertically and disposed at a level lower than that of said first named lever, and means connecting said levers, said connecting means including a tension spring. 110

3. A wire-tension device comprising a table, a pair of wire guides respectively disposed at opposite sides of the table for guiding an axially movable wire across said table, a presser block disposed above said table and having limited vertical movement in respect to the table, said presser block having a groove in its lower face for engaging with the portion of the wire which extends across said table, a lever swingable vertically for imposing a downward pressure on said block, a second lever swingable vertically and disposed at a level lower than 120 125 130

that of said first named lever, means connecting said levers, said connecting means including a tension spring, and means for releasably holding said second named lever 5 against swinging movement from a desired position in respect to the first named lever.

4. In a wire tension device, a pair of horizontal spaced apart guide members having a plurality of pairs of axially aligned 10 openings through which wires may be extended, a table disposed between said guide members having a plane upper surface over

which said wires will pass, a vertically movable presser block for each wire, said presser block being disposed above said table and having a transverse groove in its lower face for engaging the particular wire with which the block is associated, spring pressed means resisting movement of said presser blocks away from said table, and a single means 15 whereby the resistance of all of said spring pressed means can be varied at will. 20

AUGUSTUS HERBERT BRAID.
